AUTOMATIC DEFROSTING REFRIGERATION SYSTEM

Albert S. Barfield, Atlanta, Ga., assignor to
C. Dudley Shreve, Washington, D. C.

Application March 26, 1941, Serial No. 385,357

5 Claims. (Cl. 62—115)

1

Generically this invention relates to mechanical refrigeration but it is more particularly directed to show case refrigeration.

An important object of this invention is the provision of a defrosting system in connection with a conventional refrigerating system wherein a time controlled electromagnetically operated apparatus is utilized for intermittently cutting out the conventional refrigerating circulation system and substituting, for a predetermined interval, a defrosting circulating system, and especially adapted to quickly effect the substitution when such interval occurs under low pressure conditions between operating cycles.

In automatically and intermittently by-passing hot gases around the condenser and through the cooling coils for effecting defrosting of the latter in connection with mechanical refrigerating units or systems, wherein a pressure switch in circuit with the motor is employed, it has been found that upon initiating the defrosting operation during an idle period of the compressor, there is not sufficient pressure to operate the switch, but by blocking the hot gas line and directing the residual or trapped charge of gases in the hot gas line communicating with the compressor and the pressure switch there is sufficient pressure, even under such low pressure conditions, to effect quick starting of the motor and compressor. Therefore, one of the principal objects of this invention is the provision of a cut-off valve means in circuit with the motor, mounted in the hot gas line, and adapted to be closed simultaneously with stoppage of the compressor, whereby, upon initiation of the defrosting operation, the charge of said trapped gases will be directed to the pressure switch to close the motor circuit and effect quick starting of the compressor. The opening of said cut off means will also permit flow of the hot gases to and through said cooling coils during the defrosting operation.

More specifically, a further object of this invention is the provision of a defrosting apparatus in combination with a refrigerating machine, which combination includes a motor, a compressor driven by the motor, a hot gas line communicating with the compressor for circulating hot gases through the cooling coils of the refrigerating device to effect their defrosting, a pressure switch in communication with said compressor and said hot gas line and in circuit with said motor, a pair of electro-magnetic valves mounted in said hot gas line, one of said valves being in circuit with a time control mechanism and closed during the refrigerating operation,

2

the other valve being connected in the motor circuit, open when the compressor is running and closed when the compressor stops. During the idle period of the compressor, the pressure in the line to the pressure switch drops, and when the time control mechanism operates to commence the defrosting period when the compressor is not running, there is not sufficient pressure to immediately operate said pressure switch. Therefore as the said time device initiates the defrosting period the valve in circuit therewith is opened permitting the charge of gases in the hot gas line, which has been prevented from flowing to the cooling coils by the other valve, to be immediately directed to the pressure switch which closes the motor circuit and effects quick starting of the compressor. At the same time said other valve is opened to permit the flow of the hot gases through the cooling coils during the defrosting operation.

With these and other objects in view, which will become apparent as the description proceeds, the invention resides in the construction, combination and arrangement of parts, hereinafter more fully described and claimed, and illustrated in the accompanying drawings, in which like characters of reference indicate like parts throughout the figures, of which:

Fig. 1 is an elevational plan view of a refrigerating system partly in section in conjunction with my improved defrosting system and including the wiring diagram.

Fig. 2 is a detail view of the manner of securing the free end of the feeler tube.

The usual procedure of manually cutting off the refrigeration to defrost the coils and permitting atmospheric temperature to sufficiently heat the coils to melt the encrusted ice formation presents many disadvantages, in that, often too long a time elapses before cutting off the refrigeration, and, also the time required to completely effect the defrosting operation is such as to frequently permit the interior of the showcase or other unit to become warm, thereby causing readily perishable articles such as fish, meats, and the like to spoil, and, therefore, it was to overcome such disadvantages and to effect an automatic defrosting apparatus having a control pressure switch in circuit with the motor, a time control valve mechanism for determining uniform defrosting periods, and means for automatically effecting by-passing of the hot gases around the condenser and directly through the cooling coils for quickly defrosting said coils, and including means automatically settable by stopping of the

compressor to interrupt, upon starting of the compressor, the residual or trapped charge of the hot gases to the cooling coils at the beginning of the defrosting period, occurring during an idle period of the compressor, to operate said pressure switch and effect quick starting of the compressor and at the same time return said settable means to open position to permit flow of said gases through said coils during the defrosting period, and which I have accomplished by my improved defrosting system including the structural arrangement of the interrelated electrically controlled solenoid or electromagnetically operated valves, pressure switch, and time control mechanism.

In the illustrated embodiment characterizing this invention there is shown a showcase or other refrigerating box 1, a cooling coil supporting or fin structure 2, which is adapted to support the cooling coils 3, under which is suitably supported the drip pan 4, said coil supporting structure 2 being suitably connected to and supported by said case adjacent top 5.

Suitably mounted on a frame supporting structure 6 is a motor 7 adapted to operate compressor 8 by a belt or other driving connection 9. Mounted on compressor 8 is a header 10 and a pipe section 11 connecting said header and T connection 12 through which the heated compressed gaseous refrigerant is directed to the condenser 13 which discharges into receiver 14, said condenser 13 being suitably supported by frame sections 16 carried by frame 6. The refrigerant line 17 effects communication between receiver 14 and expansion valve 18, which latter is connected by pipe section 19 with the T connection 20, and therewith forming a continuation of line 17 is conduit section 21 which extends upwardly and enters the coil supporting structure 2 as at 22, forming within said structure the cooling coils 3, and extends downwardly from outlet 23 as return or suction line 24 to the inlet end of the coil 25 and from the outlet end of said coil as section 26 to header 10 for returning the refrigerant from coil 3 through coil 25 and back to compressor 8 for recirculation therethrough and through condenser 13 during the refrigerating cycle.

A feeler tube 35 has one end closed and attached to coil 25 by a clamp 36 secured by fastening means 36' and its other end suitably attached to expansion valve 18, so that temperature variations of coil 25 will be transmitted to and effect operation of said expansion valve to control the flow of the refrigerant and its refrigerating action within predetermined temperature limits and operating requirements during the refrigerating cycle.

In order to by-pass the hot gases from compressor 8 through coils 3 and 25 and back to said compressor without passing through the condenser 13, for the purpose of defrosting said coils, as will be hereinafter more fully explained, a hot gas conduit 27 is connected at one end to the T connection 12 and at its other end to the solenoid or electromagnetically operable valve C by connection 27', said valve being closed during the refrigerating operation. Valve C is connected by threaded pipe connections 28, 29, and intermediate T section 30 to the solenoid valve D which is open when the motor is running, said valve D being connected by threaded pipe section 31 to check valve 32, and connecting structure 33 to one end of pipe 34, the other end of which is suitably connected to T section 20 as at 21'.

From T 20 said hot gases pass through conduit or pipe section 21, coil 3, pipe 24, coil 25, pipe section 26, header 10, compressor 8, pipe section 11, and T 12 to conduit 27 for recirculation through the coils during the defrosting operation or cycle and without passing through the condenser 13, as will be apparent.

An auxiliary hot gas pipe or conduit 37 has one end attached by connection 38 to T section 30 and the other by connection 39 to check valve 40 suitably connected to T section 41 which is connected on one side by section 42 to pressure switch B. The other side of said T section 41 is secured by connection 43 to one end of pressure line 44, the other end of said line being connected to compressor 8 as at 45.

The time control switch, electrical connections for controlling motor 7, pressure switch B and solenoid valves C and D for effecting predetermined passage of the heated gases from the compressor without passing through the condenser 13, will now be described, and with particular reference to the solenoid D and auxiliary conduit 37 for directing and conducting the charge of said heated gases trapped in hot gas line 27 to effect operation of the pressure switch, when the defrosting operation is to be initiated by the starting of the compressor.

The electrical system for operating the various components of the apparatus comprises conductor 46 extending from the positive side of a source of electrical energy (not shown) to supply terminal 47 of junction box E and conductor 48 from supply terminal 49 to the negative side of said source of supply completing the supply circuit to the junction box. The junction box E has feed terminals 50 and 51 connected with the supply terminals 47 and 49, respectively.

For brevity of description the remaining circuits will be described as completed from the feed terminal 50 to feed terminal 51, since said terminals are connected to supply terminals 47 and 49, respectively, and therefore the respective circuits are in fact completed to said source through the supply circuit.

The time clock operating circuit comprises conductor 52 extending from feed terminal 50 to terminal 53 of time clock A and conductor 54 from terminal 55 to terminal 51, which completes the clock operating circuit.

The solenoid C circuit through said time control switch comprises conductor 56 extending from feed terminal 50 to switch terminal 57, switch 58, terminal 59, and conductor 60 to solenoid C and from said solenoid conductor 61 back to feed terminal 51 of said junction box when said switch 58 is in circuit closing position.

The motor circuit comprises conductor 62 from feed terminal 50 to motor 7 and conductor 63 from said motor to terminal 64 of pressure switch B, switch element 65, terminal 66, and conductor 67 to feed terminal 51, which completes the circuit to the motor when switch 65 of pressure switch B is in circuit closing position. In order that solenoid valve D will be in open position when the compressor is in operation and closed when it is not, said solenoid D is connected to the motor circuit. Conductor 68 leads off from conductor 62 and extends to solenoid D and conductor 69 from said solenoid to conductor 63, completing the solenoid D circuit.

While the operation of the apparatus and especially my improved defrosting system would seem to be clear from the above description, it might be well to further state that when the

apparatus is in normal refrigerating operation the motor 7 operates compressor 8 to compress the refrigerant and it passes in a gaseous form from header 10 to pipe section 11, T 12 through the condenser 13 into receiver 14, through conduit 17, expansion valve 18, pipe section 19, T section 20, conduit 21, through cooling coil 3 within the box or showcase 1, and from said coil through the return or suction line 24, coil 25, and conduit 26, back to header 10 for recirculation as in the first instance, during the refrigerating operation.

The expansion valve 18 is set for responsive operation as, for instance, between 30 degrees and 40 degrees so that when the temperature in the box reaches 30 degrees the expansion valve closes, stops the flow of the refrigerant and when the temperature of said box rises to about 40 degrees the expansion valve opens and again permits refrigerant flow.

In order to effect automatic defrosting of the device the time clock A is set to operate the time switch or circuit maker and breaker 58 to close the solenoid C circuit and open its valve to initiate the defrosting period, the opening of which valve permits the heated gaseous refrigerant to be by-passed around condenser 13 through hot gas line 27, valve C, pipe sections 28, 29, 30, valve D, sections 31, 32, 33, and conduit 34 to T section 20 and through pipe 21, coil 3, pipe 24, coil 25, and pipe section 26, back to header 10, and through the compressor for recirculation through said coils during the defrosting period. At the end of said period the clock operates switch element 58 to open the solenoid valve C circuit to close said valve and cause the hot gases to pass through condenser 13 and repeat the refrigeration action as before. However, when the time clock operates to initiate the defrosting operation during an idle period of the compressor, there is not enough pressure built up to operate the switch B and start the motor, and to overcome this disadvantage and under such conditions effect quick starting of the motor and compressor, the solenoid or electro magnetically operated valve D is connected in the motor circuit so that stopping of the motor closes said valve, whereby upon the opening of valve C at the beginning of the defrosting period the residual or trapped charge of hot gases is caused to pass from section 27 and through auxiliary hot gas line 31 to pressure switch B operating circuit breaker 65 to close the motor circuit and start operation of the compressor and at the same time valve D is opened so that the hot gases pass through the cooling coils to effect their defrosting during a predetermined time period as heretobefore described, and which may be 15 minutes, 30 minutes, or any desired period, depending upon setting of the time clock.

It will thus be apparent that I have designed an automatic defrosting system adapted to effect, not only under normal operating conditions automatic defrosting of the coils at predetermined time intervals, but when the beginning of the defrosting period occurs when the compressor is not running, to at once build up sufficient pressure to operate pressure responsive switch B and quickly effect starting of the compressor and the operation of the defrosting system substantially immediately following the operation of the time clock initiating said defrosting period, said system being simple in construction, manufactureable at a minimum cost, and efficient for the purposes intended.

Although I have found in practice that the form of my invention illustrated in the accompanying drawings and referred to in the above description as the preferred embodiment is the most efficient and practical, yet realizing that conditions concurrent with the adoption of my invention will necessarily vary, I desire to emphasize that various minor changes in details of construction, proportion and arrangement of parts, may be resorted to within the scope of the appended claims without departing from or sacrificing any of the principles of the invention.

Having thus described my invention, what I desire protected by Letters Patent is as set forth in the following claims:

1. A defrosting refrigeration circulation system including a compressor and a refrigerating coil, a branched conduit interposed between the pressure side of the compressor and said coil, one of the branches of said conduit constituting a passage for a refrigerant and including a condenser, the other branch of said conduit forming a passage for a hot defrosting gas from the compressor to said coil, pressure responsive means in communication with said hot gas passage, a time controlled electroresponsive means within said hot gas passage intermediate the compressor and point of communication of said pressure responsive means with said hot gas passage, and operable, to permit flow of a charge of hot gas from the compressor, to said pressure responsive means to effect quick starting of the compressor, and a second electroresponsive means within said hot gas passage intermediate said point of communication of said pressure responsive means with said hot gas passage and said coil operable coincidently with the starting of the compressor to permit flow of hot defrosting gas through said coil during the defrosting operation.

2. A defrosting refrigeration circulation system adapted for intermittent operation including a motor, an energizing circuit for the motor, a compressor driven by said motor, and a refrigerating coil, a branched conduit interposed between the pressure side of the compressor and said coil, one of the branches of said conduit constituting a passage for a refrigerant and including a condenser, the other branch of said conduit forming a passage for a hot defrosting gas from the compressor to said coil, pressure responsive means in said motor circuit and in communication with said hot gas passage at a point intermediate its length, a time controlled electroresponsive valve means within said hot gas passage intermediate the communication point of the pressure responsive means with said hot gas passage and the compressor, and operable, when the defrosting operation is about to occur during an idle period of the compressor and when the prevailing pressure condition in the system is insufficient to operate the pressure responsive means, to open position to permit flow of a charge of hot gas trapped in the hot gas conduit intermediate said time controlled valve and the compressor, to said pressure responsive means to effect quick starting of the compressor, and a second electroresponsive valve means within said hot gas passage intermediate said communication point of the pressure responsive means and the coil and in the motor circuit, operable simultaneously with the starting of the motor to permit flow of hot defrosting gas through said coil during the defrosting operation.

3. A defrosting refrigeration circulation system adapted for intermittent operation includ-

ing a motor, an energizing circuit for the motor, a compressor driven by said motor, and a refrigerating coil, a branched conduit interposed between the pressure side of the compressor and said coil, one of the branches of the conduit constituting a passage for a refrigerant and including a condenser, the other branch of said conduit forming a primary passage for a hot defrosting gas from the compressor to said coil, pressure responsive means in said motor circuit and in communication with the compressor, an auxiliary hot gas passage connecting the pressure responsive means with the primary hot gas passage, a time controlled electroresponsive means within said primary hot gas passage intermediate the point of connection of said auxiliary gas passage therewith and the compressor, and operable, when the defrosting operation is about to occur during an idle period of the compressor and when the prevailing pressure condition in the system is normally insufficient to operate the pressure responsive means, to open position to permit flow of a charge of hot gas from the primary hot gas passage, through the auxiliary passage to said pressure responsive means to operate the latter and effect quick starting of the compressor, and a second electroresponsive means within said primary passage intermediate said point of connection of the auxiliary gas passage with said primary passage and the coil and in said motor circuit operable simultaneously with starting of the compressor to permit flow of hot gas through said primary passage to and through said coil during the defrosting period.

4. A defrosting refrigeration circulation system adapted for automatic periodic operation including a motor, an energizing circuit for the motor, a compressor driven by said motor, and a refrigerating coil, a branched conduit interposed between the pressure side of the compressor and said coil, one of the branches of said conduit constituting a passage for a refrigerant and including a condenser, the other branch forming a hot gas passage by-passing the condenser and communicating with said coil, a pressure responsive means in said motor circuit and communicating with the compressor and said hot gas passage, a time controlled primary solenoid valve mounted in said hot gas passage intermediate the pressure responsive means point of communication with said hot gas passage and the compressor, and operable to open position to permit flow of a charge of hot gas from said hot gas passage to said pressure responsive means to effect immediate starting of the compressor, and a second solenoid valve in said motor circuit adapted to close upon stoppage of said motor,

said second valve being mounted in said hot gas passage intermediate the coil and said point of communication of the pressure responsive means with said hot gas passage, and operable simultaneously with the starting of the compressor to permit flow of hot gas to the coil during the defrosting operation.

5. A defrosting refrigeration circulation system adapted for automatic periodic operation including a motor, an energizing circuit for the motor, a compressor driven by said motor, and a refrigerating coil, a refrigerant conduit leading from the high pressure side of the compressor to the coil and including a condenser, a conduit constituting a primary hot gas passage extending from said pressure side of the compressor to said coil and by-passing said condenser, a pressure responsive means in said motor circuit and in communication with the compressor, an auxiliary hot gas passage leading off from said primary passage and communicating with said pressure responsive means, a solenoid valve mounted in the primary passage intermediate the auxiliary passage lead off point and the compressor, said valve being in circuit with a time controlled mechanism adapted to determine the defrosting period, and operable when the defrosting period is initiated while the compressor is idle and when the prevailing pressure condition in the system is insufficient to operate the pressure responsive means, to permit passage therethrough of a charge of hot gas from the primary hot gas passage through said auxiliary passage to operate said pressure responsive means and effect quick starting of the compressor, and a second solenoid valve mounted in said primary hot gas passage intermediate said auxiliary passage lead off point and said coil and in the motor circuit and adapted to close upon stoppage of the compressor and operable simultaneously with the starting of the compressor to permit flow of hot gas to said coil during the defrosting operation.
